COMBINED TRICYCLE AND CAB

James Hsu, Great Neck, N. Y.

Application July 6, 1950, Serial No. 10,971

Term of patent 14 years

(CL. D34—15)

To all whom it may concern:

Be it known that I, James Hsu, a citizen of the Republic of China, residing at Great Neck, in the county of Nassau and State of New York, have invented a new, original, and ornamental Design for a Combined Tricycle and Cab, of which the following is a specification, reference being had to the accompanying drawing, forming a part hereof, wherein:

Fig. 1 is a perspective view of a combined tricycle and cab showing my new design;
Fig. 2 is a plan view of the same;
Fig. 3 is a rear view thereof, and
Fig. 4 is a sectional view taken along the line 4—4 in Fig. 1 showing the wheel shield separately for purposes of better illustration.

I claim:

The ornamental design for a combined tricycle and cab, as shown.

JAMES HSU.
